UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

BAGGING-MACHINE.

992,148.

Specification of Letters Patent. Patented May 16, 1911.

Application filed March 8, 1906. Serial No. 304,814.

To all whom it may concern:

Be it known that I, ADELMER M. BATES, a citizen of the United States, residing at Cleveland, in the county of Cuyahoga and State of Ohio, have invented a certain new and useful Improvement in Bagging-Machines, of which the following is a specification.

My invention relates to bagging machines, and has for its object to provide new and improved constructions in apparatus of that character.

The invention is illustrated in the accompanying drawings, wherein—

15 Figure 1 is a vertical sectional view, Fig. 2, a horizontal sectional view on line 2—2 of Fig. 1, parts being omitted for the sake of clearness of illustration; Fig. 3, a detail vertical section on line 3—3 of Fig. 2, on an enlarged scale. Fig. 4, a horizontal section on line 4—4 of Fig. 3; Fig. 5, a diagrammatic illustration of a portion of the circular track; Fig. 6, a plan view of one of the bag supporting pans with parts in section; Fig. 7, a detail plan of the jiggling table; Fig. 8, a section on line 8—8 of Fig. 7; Fig. 9, a detail view of the shut-off finger, and Fig. 10, a similar view of one of the opening cams.

30 Like letters of reference indicate like parts in all the figures.

The invention relates to a machine for automatically filling and weighing bags or such like receptacles. In its general scheme it consists of a filling receptacle or hopper with which is associated a number of filling devices, it being the object of the invention to simultaneously fill several bags. The bags are connected with the filling devices and these rotate in unison. Each bag makes a complete circuit of the machine. During this cycle the bag is filled, weighed and discharged. I have also provided means for packing the material in the bag. These operations can be performed automatically through the instrumentality of the constructions which I have shown and shall describe. I wish it to be understood, however, that I do not desire to be limited to

the exact details of construction shown and described for obvious modifications will occur to any persons skilled in the art. Certain parts or certain operations might be omitted and others substituted in their place without departing from the spirit of my invention. For purposes of illustration I shall consider the machine as constructed for the purpose of filling suitable valve bags, that is, bags which are to be filled through relatively narrow valved openings, and I shall suppose that these bags are to be filled each with ninety-five pounds of cement.

The machine will be supported on a suitable base board or flooring A, upon which rests a standard B having a central bearing block B¹ through which extends the main shaft C. The shaft C has keyed thereto a worm C¹ in a housing C² which may be secured by hangers C³ C³ to the rafters C⁴ C⁴ supporting the flooring A. A worm C⁶ on the shaft C⁵ drives the worm C¹. Keyed to the shaft C is the hub D which bears upon the block B¹ and carries the ring D¹ to which are pivoted a plurality of yokes E¹ which serve as supports for the bags. Above the hub D is a hub F also keyed to the shaft C and carrying a ring F¹ strengthened by the webs F². The ring F¹ has the inwardly sloping flange F³ which supports the cone F⁴. The cone F⁴ extends into a feeding chamber or hopper formed by a casing G. This casing I have shown as cylindrical and closed at the top by a disk G¹ having a flange G² and a central upstanding hub G³ which is mounted in a stationary bearing G⁴ supported by the channel bars G⁵ G⁶. The material enters the feed chamber or hopper, which I shall designate generally by the letter G⁶, through a feed pipe G⁷ which extends into the hub G³. An internal flange G⁸ on the hub forms a packing chamber G⁹ which is closed at the top by the nut G¹⁰. This prevents the escape of material at the point of connection between the stationary feed pipe and the rotating hub G³. This is an important feature when the machine is used for han-

dling such material as cement. A stirring rake G^1 is secured to the pipe G^1 and extends down into the throat formed between the cylinder G and the cone. This device 5 serves to prevent the material from clogging. The bags are supported by suitable devices carried by the yokes E . One of these yokes and its associated parts is shown in Fig. 6. The yoke, it will be seen, is pivoted to a 10 lug D^2 on the ring D by means of a pin D^3 . At the outer end of the yoke is a lug E^1 (Fig. 1), in which is journaled a roller E^2 which travels over a track H . Centrally on the yoke are the knife edges E^3 E^4 on which 15 is supported the bag holding pan E^4 which has the upstanding curved back rest E^5 partially inclosing the bag.

In Fig. 1, the dotted lines J indicate the 20 position of the bags. The back rest E^5 carries a lug E^6 to which is pivoted the link E^7 connected with one of the webs F^2 on the hub F .

The ring F^1 has the peripheral recesses 25 F^3 F^5 and under these recesses are placed cups or receptacles K K into which the material is fed from the feeding chamber G^6 . The ring F^1 , it will be understood, closes the feeding chamber G^6 at the bottom except for the apertures formed by the recesses F^5 .

30 The cups K are preferably secured to the under side of the ring F^1 by means of screws K^1 as is shown in the detail view of Fig. 3. The parts of the cups K extending outside of the feeding chamber are closed by the 35 covers K^2 which set into a flange K^3 on the side of the cups and are secured thereto by screws K^4 . Extending from each of the cups K is a filling tube K^5 preferably under cut as shown at K^6 and having the off-set K^7 40 at the top. The bags are hung on these tubes, the tubes extending through the filling openings. The bags are preferably held in place by clips L normally held pressed against the tubes by springs L^1 .

45 The material is fed from the cup through the filling tubes by means of a rotary propeller. I have here shown a two wing curved propeller M located in each of the cups K . The propeller in each case is secured to the end of an upright shaft M^1 which turns in bearings M^2 , M^3 on the cylinder G and carries at its upper extremity 50 a pinion M^4 which engages with a gear wheel M^5 rigidly secured on a driving pulley M^6 mounted upon the hub G^3 which may be driven from any desired source of power, by the belt M^7 . The shaft M^1 passes through an aperture in the cover K^2 and this connection between the parts is made dust proof by 55 means of a packing chamber M^8 formed in a bearing block M^9 , this packing chamber being closed by the nut M^{10} . In order to prevent any lubricant from getting into the cement from the bearings of the shaft M^1 , a

drip M^{11} is placed below the bearing M^2 and 60 under this, a cup M^{12} . A bushing M^{13} is preferably inserted around the hub G^3 . The several bearings M^9 are formed on a ring M^{14} .

65 It will be understood from the foregoing that in the operation of the machine the shaft C will be kept in rotation, carrying 70 with it the elements of the feeding chamber, the separate centrifugal feeders, the bag supports and the bags, the weight of the latter being borne by the rail H . The material may be fed continuously or at intervals 75 into the feed chamber G^6 and will pass down into the cups K and from there be fed through the filling tubes into the bags. 80 The feeding devices will be so organized that the filling of the bags will be complete with one rotation of the central shaft. In order that the weight of the material in the 85 filled bag should be uniform, I have provided certain automatic weighing devices which act in conjunction with the means for shutting off the feed to the bag when it has been filled to the proper extent. The general arrangement of these devices contemplates shutting off the feed when the bag 90 shall have been filled to within a pound or two of the desired weight, this occurring when the cycle of the particular bag in question has been almost completed. The bag, 95 in continuing its circular movement, will be carried upon a scale and the feeding operation automatically resumed and then shut off precisely when the desired weight is obtained.

100 The shut-off I associate preferably with the filling tube K^5 . It will be understood that each filling tube is so provided with a shut-off. It will not be necessary to describe but one of these sets of apparatus.

105 Referring particularly to Figs. 3 and 4, N is a standard fixed upon the cover K^2 and to this standard is pivoted an arm N^1 to which is secured a shut-off valve or blade N^2 , which extends into the front of the cup K so as to shut off the filling tube K^5 . The arm N^1 carries a roller N^3 which, in the beginning of the travel of the particular filling apparatus, comes into contact with an opening cam O secured to the inside of a rail O^1 supported from some stationary part of the machine, for example by the brackets O^2 . This cam, as shown in Fig. 10, may be in the form of an inclined flange on a plate O^3 , the plate being adjustably secured to the cam rail O by the bolts O^4 O^5 which pass through the slot O^6 . The full line position of Fig. 3 shows the arm N^1 at the top of this cam with the filling tube open. The dotted line shows the arm in its lower position with the tube closed. Associated with the arm N^1 is a latch device adapted to hold the arm in its upper position. Mounted in bearings N^4 , 115

N⁶ on the standard N is a shaft N⁶ carrying a latch N⁷ secured thereto by the pin N⁸. A coil spring N⁹ engages the latch and the standard N. This spring is under tension 5 when the arm N¹ is in the dotted position and the latch N⁷ engages said arm to prevent rotation of the shaft. When the arm N¹ rides over the cam O the lifting of the arm N¹ releases the shaft N⁶ and the spring will 10 rotate the shaft N⁶ so as to bring the latch N⁷ under a hardened metal piece N¹⁰ in the lower side of the arm N¹. The arm will, therefore, be maintained in its upper position and the filling tube open until the latch 15 shall be tripped, as will next be described.

Associated with the rail O¹ is an adjustable shut-off trip, this device being shown in detail in Fig. 9. It consists of a finger P, which I prefer to construct in one piece, with the block P² provided with the clips P³ P³ which make a sliding connection with the rail O¹. Secured to the block by rivets P¹ P¹ is a rod P⁴ which is preferably flexible and passes through the guide P⁵ on the rail O. The end of the rod is provided with a hand grip P⁶. The position of the finger may thus be varied at the will of the operator. The finger P stands in the way of a finger N¹¹ on the shaft N⁶ and consequently 30 trips the latch N⁷ so that the arm N¹ is carried down to its closing position by a V-shaped spring N¹². The middle part of this spring bears upon the arm N¹ while the ends are secured to the ring M¹⁴ by the nuts N¹³ N¹³. 35 The finger P is placed at a point on the machine at which the bags will have been filled to within a small amount of the weight desired. Its position may be varied according to the particular kind of material being handled. When set in one position it will ordinarily not be necessary to reset it for the same kind of material and while 40 conditions remain substantially unchanged. For example, when the machine is to make packages of ninety-five pounds, the shut-off will be set so as to operate when about ninety-two or ninety-three pounds of material have been fed into the bag.

During the travel of the bag around the machine, the yoke E which carries it will be supported by the roller E² which runs on a track H. This track is supported in any desired manner, as for example, on standards H¹ H¹ resting on a pile of blocks H², H², the number of which may be varied 55 so as to adjust the rail to the track to different heights according to the size of bags handled. Any other sort of adjustment might, of course, be substituted for this arrangement. After the bag has passed a short distance beyond the trip finger P, the roller passes upon a separate track section H³ which is carried by the weighing device.

This apparatus may comprise any desired

form of scale, the parts being preferably arranged so as to automatically cause the insertion in the bag of an amount of material necessary to make up the desired weight. In the drawings I have shown a scale platform R upon which are the adjustable standards H¹ H¹ similar to those which support the fixed section of the track. R¹ represents the scale beam suitably supported on the frame work R², and R³, the weights. A four sided frame work R⁴ pivoted on the 70 brackets R⁵ R⁵ is connected by the extension R⁶ of one of its sides with the scale beam R². The forward member of this frame R⁷ is preferably formed on an arc corresponding with the cam rail O and carries a number 75 of depending teeth or fingers R⁸. The mechanism connecting the scale beam and the platform is of any customary construction. As illustrated in Fig. 1 there is shown one form of usual construction 80 wherein the platform R is connected to the levers W and W¹. The lever W supports one side of the platform and is mounted upon the part W² attached to a suitable supporting device. The other side of the platform is supported by the lever W¹ which is supported on a similar device W³. The levers are pivoted together at W⁴ and the lever W is connected to the connecting rod R¹¹, which in turn is connected to the scale 90 beam R¹.

It will be seen that when the platform R is moved down by the proper weight of material, the rod R¹ will be moved down. This movement will lift the scale beam R (see Fig. 2) and since the frame R⁴ is connected thereto beyond its pivotal connection to the parts R⁵, it will be seen that this upward movement of the scale beam R¹ produces a downward movement of the 100 frame R⁴.

On the cam rail O¹ at a place corresponding to the place where the roller of the bag in question passes onto the section of the track supported by the scale, is an opening cam O⁶, which in its construction and operation is similar to the opening cam O. The roller N will ride over this cam as the bag carrying yoke moves from the stationary track to the scale and thereupon the shut-off blade or valve N² will be withdrawn from the filling tube K⁵ and the operation of filling the bag will be resumed. By this time, it will be seen, the trip finger N¹¹ will have passed under the series of fingers R⁸. 110 When the weight on the scale, due to the addition of material in the bag, shall have reached the weight at which the scale is set, the scale beam R¹ will be raised and the forward end of the frame R⁴ will be tilted 115 downward causing the trip finger N¹¹ to be engaged between two of the fingers R⁸. The bag carrying and filling device will, of 120 125

course, be continuing its revolution around the axis of the machine and this motion will turn the trip finger, releasing the arm N^2 which will be carried down by the spring N^{12} 5 to shut off the feed. The bag will then pass off the scale, making room for the next bag which has, of course, undergone the process of filling in the same manner. On the cam rail O^1 at this point is located a cam which 10 serves to lift up the bag clip L against the tension of its spring L^1 . This cam S is shown in Fig. 3 as hung from a cam rail O^1 by means of a plate S^1 adjustably connected with the cam rail by the bolts S^2 S^3 . The 15 clip L is formed with an off-set L^2 which engages and rides over the cam. It will be observed that this cam extends for a considerable distance, thus raising the clip so that the filled bag may be removed and the 20 new bag put in its place.

I have also shown an automatic device for removing the bags from the filling tubes and discharging them from the machine. This consists of a curved arm T supported 25 on an upright T^1 and standing in the path of the bag just after it leaves the scale. The upper part of the bag comes in contact with this arm and the bag is pushed out of the pan E^4 . The chute T^2 is arranged to receive 30 the bag as it leaves the machine. To facilitate the removal of the filled bag from the filling tube the section of track H^3 on the scale is raised somewhat above the stationary part of the track. The ends of the 35 stationary track H are, therefore, sloped a trifle as shown at H^4 H^4 . This clearly appears in the diagrammatic view of Fig. 5.

In order to insure the proper packing of the material in the bags I provide apparatus 40 for agitating or jiggling the bags during the process of filling. This apparatus is shown in detail in Figs. 1, 2, 7 and 8. It consists of a circular table formed by three metal rings U U U with spacers U^1 U^1 between 45 them. The table has a plurality of recesses U^2 U^2 and in these recesses are mounted on the pins U^3 the hubs U^4 of a number of arms U^5 associated with eccentrics U^6 on the shaft U^7 journaled in bearings U^8 in the central 50 standard B and bearings U^9 on the base board or flooring A . These shafts carry on their inner ends beveled pinions U^{10} meshing with the beveled pinion U^{11} loose on the shaft C and supported by a collar U^{12} on 55 such shaft. One of the shafts U^7 has a pulley U^{13} on its outer end, this pulley being driven by the belt U^{14} from a source of power not shown. The jiggling table as thus described, carries three concentric upstanding rings U^{15} U^{15} U^{15} which may be strengthened by the metal rings U U U . The pans E^4 which hold the bags are provided with three apertures or slots E^8 E^8 E^8 60 and the upstanding rings of the jiggling table

reach the bag through these slots. It will 65 be observed that these upstanding or jiggling rings do not extend all the way around the table, being omitted at the front part of the machine, that is, from the point where the shut-off occurs to a point a little beyond 70 where the new bags are placed upon the machine. In order to adjust the height of the jiggling table in accordance with the position of the track H , the pins U^8 are set in slots U^{16} in the metal rings U . 75

The use and operation of my device are as follows: It has been supposed, for purposes of illustration, that the machine is to be used for bagging cement in quantities of ninety-five pounds. The operator will fit 80 the bag onto the filling tube to the left of the discharging arm T in Fig. 2, the clip L being held up at this point by the cam S . The bag will hang upon the filling tube until the opening cam O is reached, when 85 the valve N^2 will be withdrawn and the material forced into the tube by the rotary propeller M . The tube, it is to be observed, is arranged substantially tangential to the circle described by the propeller and as this 90 propeller presents a curved blade to the material it will be apparent that the discharge of the material will be peripheral, that is, in a line constituting the axis of the tube. The propeller will, of course, continue its 95 rotation whether the valve is closed or open, the material being simply driven around in a circle within the cup K when the valve is down. The filling of the bag will continue until the shut-off finger P is reached. The 100 machine will be organized so that an amount of material somewhat less than that which the bag is to ultimately hold will be fed into the bag by the time it has come within a short distance of the weighing mechanism. 105 A more exact regulation may be obtained by the adjustment of the finger P on the cam rail. During all this period the bag will have been agitated by the jiggling table. The jiggling will now cease and the bag will 110 travel for a more or less short distance until the roller E^2 passes onto the rail section supported on the scale platform. Just at this point the second opening cam O^6 causes the valve to be withdrawn from the filling tube 115 and the filling begins again. As soon, however, as the required ninety-five pounds, or any other desired weight, is reached, the frame R^4 will be tilted, the latch holding up the arm N^2 automatically tripped, and the 120 feed stopped again. A further revolution of the bag will bring it against the arm T which forces it out of the pan and down the discharge chute. These steps, it will be seen, are all carried out automatically. The 125 movement of the elements of the feeding devices is not at any time interrupted, the feed being merely shut off from the bag at the

proper times. The weighing is perfectly accurate since it is accomplished after the material has entered the bags. The process of measuring thus provided for may be said to consist first of filling a bag with an amount of material gaged by the duration of the operation of the feeding device, and second, a supplementary filling to make up the discrepancy in the amount of material desired measured by weight. When the machine is used for bagging cement or such like material, it is very important that no appreciable amount of material should be allowed to escape or come into contact with bearing surfaces and that no lubricant should be allowed to get mixed with the cement. The machine of my invention meets difficulties of this sort.

It will be observed from inspection of the diagrammatic view of Fig. 5 that the scale section H^3 of the track is higher than the stationary part which is made to slope up to it at H^4 H^4 . This results in slackening the bag on the filling tube in order that the weighing may be accurately done and also to permit the final charge of material to be inserted into the bag which is presumably almost filled when the bag carrier moves onto the scale.

30 I claim:

1. In a bag filling machine, the combination of a rotary device, a bag support pivoted thereto which engages the bottom of the bag, a track, and means for movably supporting the bag support on the track.

2. In a bag filling machine, the combination of a driving shaft, with a plurality of bag supports pivoted so as to rotate with the shaft and which engage the bottom of the bags, a circular track, and means for movably supporting said bag supports on the track.

3. In a bag filling machine, the combination of a driving shaft, with a plurality of bag supports pivoted so as to rotate with the shaft, a circular track, means for movably supporting said bag supports on the track, and means for adjusting the height of the track.

50 4. In a bag filling machine, the combination of a pivoted yoke, with a bag holding device movably mounted on the yoke, and a roller associated with the yoke to support the same and a supporting device along which the roller passes.

5. In a bag filling machine, the combination of a pivoted yoke, with a bag holding device movably mounted on the yoke, a roller associated with the yoke to support the same, and a track in which the roller runs.

6. In a bag filling machine, the combination of a driving shaft, with a pivoted yoke associated therewith so as to be rotated thereby, a bag holding device movably

mounted on the yoke, and a roller mounted 65 on the yoke so as to support the same and a supporting device along which the roller passes.

7. In a bag filling machine, the combination of a driving shaft, with a pivoted yoke 70 associated therewith so as to be rotated thereby, a bag holding device movably mounted on the yoke, a roller mounted on the yoke so as to support the same and a supporting device along which the roller 75 passes, and a link from the holding device to the rotary shaft.

8. In a bag filling machine the combination of a pivoted bag supporting device with a weighing mechanism and means for 80 moving the same upon the weighing mechanism, and mechanism for substantially filling the bag before its support is moved onto the weighing mechanism.

9. In a bag filling machine the combination of a bag supporting device capable of movement vertically and horizontally, with a weighing mechanism and means for moving the bag supporting device upon the weighing mechanism and mechanism for 90 substantially filling the bag before its support is moved onto the weighing mechanism.

10. In a bag filling machine, the combination of a driving shaft, with a pivoted bag 95 supporting device connected with the shaft so as to rotate therewith, and a weighing mechanism upon which the bag supporting device is carried by the rotation of the shaft and mechanism for substantially filling the bag before its support is moved onto 100 the weighing mechanism.

11. In a bag filling machine, the combination of a track having a movable section, a weighing mechanism associated with said movable section, and means for moving the 105 bag upon such track, a support for the bag, and means for filling the bag substantially full before it enters upon the movable track section.

12. In a bag filling machine, the combination of a circular track having a movable 110 section, a weighing mechanism associated with said movable section, and means for moving the bag upon such track, a support for the bag, and means for filling the bag 115 substantially full before it enters upon the movable track section.

13. In a bag filling machine, the combination of a track having a movable section, a weighing mechanism associated with said 120 movable section, means for moving the bag upon such track, and a feeding device to feed the material into the bag during its travel upon the track.

14. In a bag filling machine, the combination of a track having a movable section, a weighing mechanism associated with said 125 movable section, means for moving the bag

- upon such track and movable section, a feeding device to feed the material into the bag during its travel upon the track, and a shut-off device operative before the bag passes 5 onto the movable section.
15. In a bag filling machine, the combination of a track comprising a movable section with a weighing mechanism associated with said section, means for moving the bag upon 10 said track, a feeding device adapted to feed material into the bag, and a shut off device for the feeding device associated with the weighing mechanism and operative when a predetermined weight has been reached.
- 15 16. In a bag filling machine, the combination of a track having a fixed section and a movable section, with a weighing mechanism associated with the movable section, means for moving the bag upon the track, 20 a feeding device for feeding material into the bag, a shut-off for the feeder operative when the bag has reached a certain predetermined position on the fixed section, means for setting the feeder in operation when the 25 bag passes onto the movable section, and means associated with the weighing mechanism for operating the shut-off when a certain predetermined weight has been reached.
17. In a bag filling machine, the combination of a driving shaft, with a bag supporting device movable vertically and associated with the shaft so as to rotate therewith, a weighing mechanism upon which the bag support is carried by the rotation of the 30 shaft, a feeding device, and means for setting the feeding device in operation when the bag holding device is moved upon the weighing mechanism.
18. In a bag filling machine, the combination of a driving shaft, with a bag supporting device movable vertically and associated with the shaft so as to rotate therewith, a weighing mechanism upon which the bag support is carried by the rotation of the 40 shaft, a feeding device, and a shut-off device associated with the scale to stop the feed when a predetermined weight has been reached.
19. In a bag filling machine, the combination of a pivoted bag supporting device, with a roller supporting the same, a weighing mechanism, means for moving said supporting device upon the scale, means for feeding the material into the bag, and a 50 shut-off device operative when a predetermined weight has been reached.
20. In a bag filling machine, the combination of a circular track comprising a fixed section and a movable section, with a bag 60 supporting device movable upon said track, a weighing mechanism associated with said movable section, a feeding device associated with the bag supporting device, controlling mechanism for said feeding device, and open- 65 ing and shut-off devices with which the controlling mechanism of the feeder engages in the travel of the bag support over the track.
21. In a bag filling machine, the combination of a weighing mechanism, with means for moving a bag across the weighing mechanism, a feeding device operative while the bag is on the weighing mechanism, a valve to control the operation of the feeding device, a latch to hold said valve open, and means actuated by the weighing mechanism for tripping the latch.
22. In a bag filling machine, the combination of a weighing mechanism, with means for moving a bag across the weighing mechanism, a feeding device operative while the bag is on the weighing mechanism, a valve to control the operation of the feeding device, a latch to hold said valve open, and means actuated by the weighing mechanism 85 for tripping the latch, comprising a plurality of depending fingers.
23. In a bag filling machine, the combination of a weighing mechanism, with means for moving a bag across the weighing mechanism, a feeding device operative while the bag is on the weighing mechanism, a valve to control the operation of the feeding device, a latch to hold said valve open, and means actuated by the weighing mechanism 90 for tripping the latch comprising a pivoted frame having a plurality of depending fingers.
24. In a bag filling machine, the combination of a bag holding device having an apertured bottom part, a jiggling device operative on the bag through said apertures, and means for filling the bag during the operation of the jiggling device and means for simultaneously actuating the filling and jiggling mechanisms.
25. In a bag filling machine, the combination of means for supporting a bag with a jiggling device having upstanding members adapted to be vibrated against the bottom of the bag, means for filling the bag during the operation of the jiggling device and means for simultaneously actuating the filling and jiggling mechanism.
26. In a bag filling machine, the combination of means for supporting a plurality of bags arranged circularly, with an annular jiggling table, and means for vibrating the jiggling table against said bags.
27. In a bag filling machine, the combination of means for supporting and moving a plurality of bags arranged circularly, with an annular jiggling table, and means for vibrating said jiggling table against said bags.
28. In a bag filling machine, the combination of means for supporting and moving a plurality of bags arranged circularly, said means having apertures, with an annular

jigging table, and means for vibrating said jigging table against said bags, said jigging table having a plurality of upstanding ribs.

29. In a bag filling machine, the combination of means for supporting and moving a plurality of bags arranged circularly, said means having apertures, with an annular jigging table, and means for vibrating said jigging table against said bags, said jigging table having a plurality of upstanding ribs arranged in an arc less than a circle.

30. In a bag filling machine, the combination of means for supporting and moving a plurality of bags arranged circularly, with an annular jigging table, and a plurality of eccentrics to vibrate the table against the bags.

ADELMER M. BATES.
